UNITED STATES PATENT OFFICE.

GEORGE W. HARLACHER, OF DOVER, PENNSYLVANIA, ASSIGNOR OF ONE-HALF TO
HOWARD E. QUICKEL, OF DOVER, PENNSYLVANIA.

LAYING CABINET.

Application filed July 27, 1925. Serial No. 46,400.

The present invention relates to poultry equipment, and more particularly to a hen's nest or laying cabinet.

An object of the invention is to provide a cabinet adapted to maintain a plurality of nests, and which may be readily cleaned.

A further object of the invention is to provide a cabinet which may be cheaply manufactured and sold at an inconsiderable 10 cost.

Another object of the invention is to afford a cabinet in which the individual nests are of extremely simple construction, may be individually removed, and are provided 15 with an extension which serves as a perch and also as a shade or visor for an adjacent nest or compartment.

Other objects of the invention are to provide means for conveniently securing the 20 nest in position, to construct a cabinet so that it may be readily increased or decreased in size, as may be desirable, and, generally, to provide a construction which enables the entire cabinet to be thoroughly 25 cleaned and disinfected. These and other objects of the invention will become clear as the description proceeds in connection with the accompanying drawings, wherein—

Figure 1 is a front elevational view,

Figure 2 is a vertical section on the line 2—2 of Figure 1.

Figure 3 is a perspective showing the cabinet frame with the nest bottoms removed.

Figure 4 is a perspective of one of the nest bottoms.

Figure 5 is a vertical sectional view of a frame or cabinet of sectional construction with some of the nest bottoms removed.

Figure 6 is a perspective of two cabinet 40 filler sections.

Figure 7 is a front elevational view of a modified construction, and

Figure 8 is a vertical section on substantially the line 8—8 of Figure 7.

Referring to the drawings for a more detailed description, the device comprises a cabinet-type of frame (Figure 3), which consists of a series of vertical partitions 10, the outer partitions being extended downwardly to form legs or supports 11, and the entire series being united by a top 12, a back closing wall 13, and a front joining strip 14. A frame thus constructed may be conveniently made from wood or any other suitable material. It will be noted that when

the nest bottoms, which form the individual compartments, are not in position, as illustrated in Figure 3, the entire interior of the cabinet is open, and may conveniently be cleansed very thoroughly. Each nest is, 60 preferably, formed by a bottom member 15, carrying a front wall 16, which may be formed integral with or otherwise fixedly secured to the bottom, the latter being provided with an extension 17, which projects 65 beyond the wall, to provide a perch, and also to serve as a visor or shade for the next lower nest or compartment when the bottoms are arranged in vertical tiers (Figures 1 and 2) in the cabinet. 70

The bottoms may be secured in position in any suitable manner, as, for instance, by providing each partition 10 with horizontal grooves 18, the grooves on opposed partitions being horizontally aligned to provide 75 guideways for the bottoms, thus enabling the latter to be slidably moved into and out of position. To prevent accidental dislodgment of the nest bottoms, suitable latch means may be provided, such as the pivot, 80 actually movable latches 19 arranged upon the partitions 10 and serving, when turned horizontally, to overlie the front wall 16 of each nest bottom. By reference to Figure 2, it will be noted that the extension 17 substantially equals the distance between the 85 top edge 16' of each front wall and the superposed nest bottom, so that the extension serves effectively to shade the lower nest, and thereby to provide the desirable dark- 90 ness in each nest.

Referring to Figures 5 and 6, the invention is here shown as embodied in a cabinet of sectional construction, permitting increase and decrease in the size of each 95 cabinet. The individual sections are, preferably, horizontally arranged, and an individual section comprises a back closing wall 20 extending across vertical partition sections 21, the front edges of the latter being united by means of a connecting strip 22, which is suitably grooved, as at 23 (Figure 5) to receive the front edges of the partition sections. It will be observed that the wall 20 at one edge 20' projects downwardly 100 below the bottoms of the partition sections, and at this upper edge is cut away, as at 20''. Likewise, the front strip 22 extends in a vertical plane beyond the adjacent horizontal edges of the partition sections, in the 105 110

present instance the lower horizontal edges, to overlie the partition sections of the adjacent main cabinet section. By reference to Figure 5, it will be observed that the front 5 strip is suitably grooved vertically to receive the partitions of the adjacent section, and thus, together with the back wall, which is also grooved (Figure 5) interlocks with the adjacent cabinet section. By providing 10 individual cabinet sections of this construction, a cabinet of considerable size may be conveniently built up, and at any time additional sections may be placed in position. Each cabinet of sectional construction includes 15 a top section 25 and a bottom section 26 having leg portions 26', these two sections being the only two which are at all different from the filler sections illustrated in Figure 6. It will be noted that the partition sections are each provided with grooves 27, which serve as guide-ways for the nest bottoms, and each partition section carries the pivotal latch members 28.

Obviously, however, a different mechanical means might be employed for retaining the nest bottoms in position, in either a cabinet of integral construction or one of the sectional construction. As illustrative of the variation of the particular means previously described, there is shown in Figures 25 7 and 8 a modification, in which there are provided a series of horizontally disposed pivot pins 30 extending through eye brackets 31 positioned upon each partition. 30 The nest bottoms are formed with grooves 32 (Figure 8) which are closed by loops or brackets 33 to provide closed bearings through which the pivot pins pass. It will be noted that a single pin 30 serves to maintain 35 in position an entire horizontal series of nest bottoms and to permit the same to be pivotally moved to and from horizontal position. With this form of device, stops 40 34 may be arranged upon the back wall 35, and the latches 28' prevent accidental movement of the bottoms. Whenever a single nest is to be examined or removed, it is 45 simply necessary to release the same by means of its latch 28', thus permitting the perch extension 17 to be depressed and raising the portion of the bottom within the cabinet. An entire horizontal series may 50 be removed by withdrawing the pivot pin 30, which carries, at one end, a cotter pin 36, 55 to hold it in working position. It will be clear that the means for supporting the nest bottoms within the cabinet may be varied, as desired, and that the invention is not limited to this feature.

60 A common characteristic of all of the forms illustrated and described is the facility with which the bottoms may be removed and the open interior construction of the cabinets when the bottoms are withdrawn. Thus there is no difficulty whatso-

ever in maintaining the device entirely sanitary, which is a highly important consideration in an article of this character. Furthermore, both the cabinet and nest bottoms are formed of interchangeable parts, which 70 enables the device to be manufactured and marketed in quantities and at a comparatively small expense.

Obviously, numerous changes may be 75 made in the construction illustrated and described, without departing from the invention, which is defined in the following claims.

I claim:

1. A device of the class described comprising 80 a frame having a plurality of vertical partitions therein, and a plurality of nest bottoms removably supported by said partitions and between the same in vertical tiers, each bottom having thereon a front wall which only partially closes the space between 85 its bottom and the superposed bottom and is removable with its bottom as a unit, each of said bottoms being extended outwardly beyond 90 said front wall to form a perch and also to serve as a shade for the next lower nest.

2. A device of the class described comprising 95 a frame having a plurality of vertical partitions therein, and a plurality of nest bottoms removably supported by said partitions and between the same in vertical tiers, each bottom having thereon a front wall which only partially closes the space between 100 its bottom and the superposed bottom and is removable with its bottom as a unit, each of said bottoms being extended outwardly beyond 105 said front wall a distance substantially equal to the distance between the top edge of each front wall and the superposed bottom to form a perch and also to serve as a shade for the next lower nest.

3. A device of the class described comprising 110 a frame having a plurality of vertical partitions therein, a plurality of nest bottoms removably supported by said partitions and between the same in vertical tiers, each bottom having thereon a front wall which only partially closes the space between 115 its bottom and the superposed bottom and is removable with its bottom as a unit, each of said bottoms being extended outwardly beyond 120 said front wall to form a perch and also to serve as a shade for the next lower nest, and latch devices on said partitions to maintain said bottoms in position.

4. A device of the class described comprising 125 a frame having a plurality of vertical partitions therein, and a plurality of nest bottoms removably supported by said partitions and between the same in vertical tiers, each bottom having thereon a front wall which only partially closes the space 130 between its bottom and the superposed bot-

tom and is removable with its bottom as a unit, each of said bottoms having open unobstructed sides whereby the partitions serve as nest sides and each being extended outwardly beyond said front wall to form a perch and also to serve as a shade for the next lower nest.

5. A device of the class described comprising a frame having a plurality of vertical partitions therein, and a plurality of nest bottoms removably supported by said partitions and between the same in vertical tiers, each bottom having thereon a front wall which only partially closes the space between its bottom and the superposed bottom and is removable with its bottom as a unit, each of said bottoms being extended outwardly beyond said front wall to form a perch and also to serve as a shade for the next lower nest, said bottoms being slidably supported by the partitions, and freely operable latch devices on said partitions adapted to engage the bottoms at the sides of the partitions to prevent outward sliding movement.

25 6. A laying cabinet comprising a frame having a plurality of vertical partitions therein, said partitions being horizontally grooved to receive between them nest bottoms arranged in vertical tiers, and nest bottoms supported by said partitions and slideable into and out of said grooves, each bottom having a front wall which only partially closes the space between the bottom and the superposed bottom and is removable with its bottom as a unit, and each of said bottoms being extended outwardly beyond said front wall to form a perch and also to serve as a shade for the next lower nest.

7. A laying cabinet comprising a frame having a plurality of vertical partitions therein, said partitions being horizontally grooved to receive between them nest bottoms arranged in vertical tiers, nest bottoms supported by said partitions and slideable into and out of said grooves, each bottom having a front wall which only partially closes the space between the bottom and the superposed bottom and is removable with its bottom as a unit, and latch means for retaining each bottom in position, each of said bottoms being extended outwardly beyond said front wall to form a perch and

also to serve as a shade for the next lower nest.

8. A frame section for a laying cabinet comprising a series of vertical partitions, a back wall uniting said partitions and closing the spaces between them, and a front strip extending across said partitions adjacent one edge and projecting vertically beyond the edges of the partitions whereby to overlap an adjacent section, said partitions being horizontally grooved to receive nest bottoms slidably between them.

9. A frame section for a laying cabinet comprising a series of vertical partitions, a back wall uniting said partitions and closing the spaces between them, a front strip extending across said partitions adjacent one edge and projecting vertically beyond the edges of the partitions whereby to overlap an adjacent section, said partitions being horizontally grooved to receive nest bottoms slidably between them, and latch devices on said partitions to retain the bottoms in position.

10. A laying cabinet comprising a frame built up of a plurality of horizontal sections, said sections each having vertical partition sections arranged with their edges abutting those of adjacent sections and each partition section being grooved to receive nest bottoms, each of said frame sections having a rear wall closing the spaced partition sections and a front strip extending across the partitions, said wall and strip being arranged to overlap an adjacent frame section.

11. A laying cabinet comprising a frame having vertical partitions adapted to receive between them a series of nest bottoms, means for removably supporting nest bottoms between the partitions, and a series of nest bottoms carried by said partitions between the same in vertical tiers, said bottoms having formed thereon a front wall which only partially closes the space between the superposed bottoms, and each bottom being extended beyond the front wall to form a perch and also to serve as a shade for the next lower nest.

In testimony whereof I have hereunto set my hand.

GEORGE W. HARLACHER.
